[57] **ABSTRACT**

Mixtures of C₁₂ bicyclic aromatic hydrocarbons containing dimethylnaphthalenes are difficult to fractionate by conventional techniques such as distillation or crystallization. However, by dissolving 2-chloro, 4-nitrobenzoic acid in such a mixture at an elevated temperature, followed by subsequent cooling, a solid complex of said acid and certain hydrocarbons is formed. Separation of the solid complex from the cooled mixture and its subsequent decomposition results in a product that is substantially richer in those dimethylnaphthalenes which have greater tendency to form such complexes. Upon further processing, these dimethylnaphthalenes have utility in the production of dyes.

BACKGROUND OF THE INVENTION

The invention relates generally to a process for fractionating difficult-to-separate C₁₂ bicyclic aromatic hydrocarbons and in particular the isomers of dimethylnaphthalenes. More specifically, it relates to a process for fractionating isomers of dimethylnaphthalene by initially dissolving 2-chloro, 4-nitrobenzoic acid in the liquid hydrocarbons.

Dimethylnaphthalenes are oxidized to naphthalene-carboxylic acids which are used in the production of dyes and pigments. A more detailed discussion of the utility of dimethylnaphthalenes appears in "Naphthalene Carboxylic Acids" by K. A. Scott in Kirk-Othmer, Encyclopedia of Chemical Technology, 2nd Edition, Vol. 13.

For convenience dimethylnaphthalene or dimethylnaphthalenes herein will be referred to as DMN with specific DMN isomers being indicated by reference to the location of the methyl groups. For example, 2,6-dimethylnaphthalene will be referred to as 2,6-DMN.

DMN are found in coal tar, lignite tar, crude oil, the drip-oil fraction produced during the pyrolysis of hydrocarbons to make olefins, in heavy petroleum reformate and in petroleum gas oil produced by catalytic cracking. In these hydrocarbon mixtures DMN are usually present in rather dilute concentration. For example, one analysis shows DMN making up about 4 percent by weight of a gas oil. However, by known processes such as distillation, crystallization and solvent extraction, DMN can be recovered in concentrated form from the previously mentioned sources. In oxidizing these DMN to carboxylic acids, it is usually preferable that each isomer be oxidized by itself since generally each isomer requires slightly different reaction conditions for optimum oxidation.

Most, if not all, the isomers of DMN usually are present in these hydrocarbon mixtures. These DMN isomers, as well as certain other C₁₂ alkyl naphthalenes such as ethyl-naphthalenes, have boiling points which are extremely close to each other. This closeness in boiling points makes it extremely difficult to distill apart the individual isomers or distill some isomers from other C₁₂ alkyl naphthalenes. These boiling points are as follows:

C ₁₂ Alkylnaphthalenes	Boiling Points, °F. *
2-ethylnaphthalene	496
1-ethylnaphthalene	498
2,6-DMN	504

1	2	
	2,7-DMN	504
	1,7-DMN	505
	1,6-DMN	505
	1,3-DMN	509
	1,5-DMN	509
5	1,2-DMN	514
	2,3-DMN	516
	1,4-DMN	515
	1,8-DMN	518

10

*API Project 44, Tables 23-2-(33.5200), 23-2-(33.5210) and 23-2-(33.5211).

Since 2,6-DMN and 2,7-DMN have the same boiling points, these isomers cannot be separated by distillation. Other such pairs are 1,7-DMN and 1,6-DMN, as well as 1,3-DMN and 1,5-DMN.

Certain DMN isomers can be separated using the differences in their freezing points. These methods are reported in U.S. Pat. No. 3,202,726 issued Aug. 24, 1965 to E. W. Malmberg et al. and U.S. Pat. No. 3,173,960 issued Mar. 16, 1965 to W. M. Robinson. However, despite differences in freezing points, various DMN isomers form eutectics, making it impossible to further separate these isomers by crystallization. For example, 2,6-DMN with a freezing point of 234° F. and 2,3-DMN with a freezing point of 221° F. form a eutectic with a freezing point of about 170° F. Thus other methods besides crystallization and distillation are needed for separating various DMN isomers from each other.

Other techniques have been suggested for purification and/or separation of DMN. U.S. Pat. No. 3,183,279 issued May 11, 1965 to I. W. Mills et al. uses selective oxidations; U.S. Pat. No. 3,155,739 issued Nov. 3, 1964 to G. Suld uses a HF-BF₃ complex. Still others have facilitated separation and/or purification by isomerizing various DMN isomers to specific isomers (See J. Org. Chem., 29, 2939-2946, 1964, G. Suld et al.).

Summarizing, the separation of DMN isomers from each other by known methods is difficult if not practically impossible. There is a need for another purification and/or separation method or a method which facilitates existing procedures.

SUMMARY OF THE INVENTION

This invention provides a process for the fractionation of C₁₂ bicyclic aromatic hydrocarbons containing DMN by selective complexation with 2-chloro, 4-nitrobenzoic acid. The acid is dissolved in the hydrocarbon mixture containing DMN, preferably at an elevated temperature. Afterwards, the resulting solution is cooled to a lower temperature and the formed solid acid-DMN complex is separated. The complex is decomposed by known methods and the subsequently released DMN has a composition substantially different from the starting hydrocarbon mixture.

DESCRIPTION

The complexing agent, 2-chloro, 4-nitrobenzoic acid, for convenience, is referred to herein as CNA. This acid is added, either as a solid or melt, to the C₁₂ bicyclic aromatic hydrocarbons mixture containing DMN. The C₁₂ liquid, during this addition, can be at either ambient or elevated temperature. However, if the resulting acid-hydrocarbon mixture remains at ambient temperature, i.e., 50° to 100° F., the rate at which the acid dissolves is very slow and the amount ultimately dissolved is very small. The small amount of acid that goes into solution at ambient temperature can be recovered as solid acid-hydrocarbon complex by lowering the temperature of the mixture, e.g., to 0° F. However, the preferred method involves using a temperature which is sufficiently high so that substantially all the added CNA will rapidly dissolve. While temperatures higher than the normal boiling point of the C₁₂ bicyclic aromatic hydrocarbon mixture can be used to dissolve the acid by employing elevated pressures, it is desirable that a lower temperature be used, preferably below the boiling point of the C₁₂ mixture and more preferably below the boiling point of the DMN.

After the CNA has dissolved, the solution is allowed to cool to 0° to 100° F. either with or without agitation. During this cooling step, a solid comes out of solution. This solid is a complex of CNA and DMN. This solid complex is separated from the liquid by conventional methods such as filtration or decantation.

It is believed that the complexes formed herein are π complexes, i.e., they are caused by combination between the π electrons of the two rings involved. The CNA apparently accepts a share in the π electrons of the compound which is complexed with it. Steric factors appear to have a strong effect, since according to the theory of π complex formation, the two rings must be close together and parallel in order for the complex to form. These complexes are distinct from the acid-base type as exemplified by complexes of HF-BF₃ and xylenes and also from clathrate complexes of, for example, the urea-paraffin type.

Some DMN isomers complex more readily than others with CNA. These differences in tendencies to form complexes can be used to facilitate fractionation of DMN isomers.

The feed to this process can include, in addition to at least two DMN isomers, other compounds that do not alter or destroy the structure of the complex. In general, appreciable quantities of undesirable compounds that will react with the acid are to be avoided. Compounds such as C₄ to C₂₀ alkanes, alkenes, cycloalkanes, cycloalkenes or mixtures thereof are relatively inert and have no appreciable effect on the complex formation. However, hydrocarbons boiling outside the boiling range of C₁₂ bicyclic aromatic hydrocarbons and which form complexes with this acid should not be present in appreciable quantities in the feed. For example, a Czechoslovakian reference, J. Slosar and V. Sterba, Chem. Prumysl., 15/40(3), pages 142-147 (1965), teaches the use of 2-chloro, 4-nitrobenzoic acid as a means of isolating 1-methyl-naphthalene. This methylnaphthalene can be excluded from the feed to the present process by using a feed having only C₁₂ bicyclic aromatic hydrocarbons containing DMN. Preferably, C₁₂ bicyclic aromatic hydrocarbons are C₁₂ alkyl naphthalenes and ideally they are only DMN.

The amount of CNA employed in the complexing step can vary over a wide range depending upon the fractionation desired. The amount of CNA is related to the amount of DMN present. Preferably, the amount of CNA dissolved in the hydrocarbon mixture is in the range from 0.01 to 3.0 moles of CNA per mole of DMN. A preferred narrower range is from 0.10 to 1.5 moles of CNA per mole of DMN. The contacting of the C₁₂ bicyclic aromatic hydrocarbons with CNA can be performed in one contacting stage or a plurality of distinct contacting stages.

The temperature above which the acid rapidly dissolves in the hydrocarbon mixture being treated can be determined by simply heating a mixture of the two while agitating and observing the temperature level at which rapid dissolution occurs. I have found, for example, that the preferred temperature for dissolving the acid in a C₁₂ bicyclic aromatic hydrocarbon mixture containing DMN is at a temperature 250° to 400° F., more preferably between 300° to 400° F. Agitation is helpful to dissolve the CNA.

While not all the acid added to the hydrocarbon mixture need go into solution, it is preferred that substantially all of it does. Since undissolved acid does not complex with DMN, any undissolved acid decreases the amount of complexation per mole of added acid and this decrease in complexation is undesirable.

After the acid has gone into solution, the solution is cooled, with or without agitation, until the CNA-DMN crystallizes out.

The solid complex is readily separated from the resulting admixture. Filtration, decantation or centrifugation can be used to remove the complex. Separation of the complex from the admixture is ordinarily performed at a temperature below about 150° F.; temperatures between 50° and 125° F. are particularly effective for CNA-DMN complex separation. Lower separation temperatures, e.g., 0° F., can also be used.

After separation, it is advisable to wash the complex with a light hydrocarbon solvent in order to remove the physically absorbed liquid mixture from the complex, after which the complex is vacuum dried. Pentane is an excellent wash solvent.

Several techniques can be employed to decompose the solid complex. The preferred procedure comprises heating the solid complex to a temperature whereby the complex is decomposed and the DMN are obtained as a distillate. The recovered acid can be recycled to the same or another contacting zone.

A second procedure for decomposing the complex involves heating in the presence of an inert solvent, such as C₄ to C₂₀ alkanes, alkenes, cycloalkanes, cycloalkenes or mixtures thereof, whereby the complex decomposes and two layers are formed one consisting of the complexing acid and the other of a solution of the DMN in a solvent. Accordingly, if a low-boiling alkane, for example, is used as a solvent, it may be necessary to use superatmospheric pressure in order to maintain the necessary decomposition temperature. The recovered DMN can be separated from the solution by evaporating the solvent.

A third procedure for decomposing the complex is to contact it with water or an aqueous base, such as aqueous sodium hydroxide. With the aqueous base, the acid becomes a salt in the resulting water layer and the organic layer is DMN. The salt in the water layer facilitates the separation of the two layers.

The following example illustrates the invention:

EXAMPLE

The CNA used was white crystals having a melting point of 283° to 286° F. The composition of the hydrocarbon mixture treated to illustrate this invention is shown in the following Table and is referred to as feed.

The feed was treated in the following manner. One mole of CNA per 5 moles of DMN present in the feed was added to the feed at room temperature. All the crystals of CNA did not dissolve. The mixture was heated and agitated at about 300° F. until a solution had formed, i.e., all the CNA had disappeared.

The resulting solution was allowed to cool. During this cooling period, the complex crystallized out. The solid complex was filtered out and subsequently washed and vacuum dried. After this washing and drying, the solid complex was placed in 10 percent aqueous sodium hydroxide and then heated until an organic layer was formed. This organic layer is the complexate containing a different percentage of DMN than the feed.

Also shown in the following Table are the ratios (weight or mole) of each specific DMN in the complexate to the same DMN in the noncomplexate. If this ratio equals one, no change in concentration occurred. If this ratio is greater than one, complexation of the specific DMN was preferential and if less than one, complexation of the specific DMN was not preferential.

TABLE

Formation of DMN-CNA Complexes

Compounds	Feed	Weight Percent		Ratio of Compounds in Complexate to Non-complexate
		Complexate	Non-complexate	
Biphenyl methylnaphthalenes Others	27.2	7.1	30.1	—
1- and 2-ethyl-naphthalene	8.2	4.5	8.4	0.54
2,6-DMN	5.2	3.2	5.7	0.56
2,7-DMN	8.3	8.1	6.8	1.2
1,6-DMN	14.1	20.8	14.0	1.5
1,7-DMN	19.1	30.8	18.3	1.7
1,5-DMN	1.0	1.8	0.7	2.5
1,4-DMN	1.3	0.6	1.2	0.5
1,3-DMN	13.6	18.3	14.0	1.3

1,2-DMN	0.6	1.7	0.2	8.5
2,3-DMN	1.3	3.1	0.6	
TOTAL	100.1	100.0	100.0	5.2

The data in the foregoing Table show that certain DMN complex to a greater extent than others. Thus, for example, the ratio of 1,7-DMN in the complexate to the same DMN in the noncomplexate is 1.7, whereas the ratio of 2,6-DMN in the complexate to the same DMN in the noncomplexate is 0.56.

C_{12} bicyclic aromatic hydrocarbon mixtures containing DMN, other than the aforementioned feed, can be fractionated in an analogous manner using the acid as a selective complexing agent.

The invention claimed is:

1. A method of fractionating a liquid mixture of C_{12} bicyclic aromatic hydrocarbons having a major amount of C_{12} alkyl-naphthalenes and containing dimethylnaphthalenes comprising:

- dissolving 2-chloro, 4-nitrobenzoic acid in said mixture at a temperature at which it is liquid to complex preferentially with at least one of the dimethylnaphthalenes and form a complex containing less than the total amount of dimethylnaphthalenes;
- cooling the resulting hydrocarbon-acid solution until solid complex of dimethylnaphthalenes and acid crystal-

- lizes;
- separating the solid complex from the resulting admixture;
  - and decomposing the solid complex to recover the resulting complexate having a proportion of dimethylnaphthalenes different from that in the starting hydrocarbon mixture.
- 5 2. A method according to claim 1 wherein the mixture of C_{12} bicyclic aromatic hydrocarbons consists essentially of a mixture of C_{12} alkylnaphthalenes containing dimethylnaphthalenes.
- 10 3. A method according to claim 1 wherein the mixture of hydrocarbons consists essentially of a mixture of dimethylnaphthalenes.
- 15 4. A method according to claim 1 wherein the amount of acid dissolved in said hydrocarbon mixture is in the range from 0.01 to 3.0 moles per mole of dimethylnaphthalenes.
- 20 5. A method according to claim 1 wherein the mixture of said hydrocarbons consists essentially of C_{12} alkyl-naphthalenes containing dimethylnaphthalenes, the amount of acid dissolved in said alkylnaphthalenes is in the range from 0.1 to 1.5 moles per mole of dimethylnaphthalenes, the dissolving occurs at a temperature in the range from 300° to 400° F. and the solid complex is separated at 0° to 125° F.
